(57) **CLAIM**

The ornamental design for a camera monitor, as shown and described.

DESCRIPTION

FIG. 1 is a top, front and right side perspective of a camera monitor showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, rear and left side perspective view thereof. The broken lines depict portions of a camera monitor in which the design is embodied and form no part of the claimed design.
